UNITED STATES PATENT OFFICE

VICTOR C. NORQUIST, OF KANSAS CITY, MISSOURI, ASSIGNOR, BY MESNE ASSIGNMENTS, TO BUTLER AIRCRAFT CORPORATION, OF KANSAS CITY, MISSOURI, A CORPORATION OF MISSOURI

AEROPLANE WING

Application filed April 11, 1929. Serial No. 354,246.

This invention relates to improvements in aeroplane wing construction, and refers more particularly to an aeroplane wing and wings constructed of a single metallic covering sheet made rigid by horizontal spars running longitudinally of the wing.

Among the salient objects of the invention are to provide a wing in which the covering material is corrugated and of sufficient thickness to give the proper rigidity and strength to the wing, this covering material being doubled back upon itself and united along the trailing edge of the wing, and to support the central portion of the wing by spars the entire surface being formed into the desired contour.

Referring to the drawings, Fig. 1 is a plan view of the wing.

Fig. 2 is a sectional view taken along the line 2—2 in Fig. 1.

Fig. 3 is a view taken on line 3—3 in Fig. 2.

Fig. 4 is a view taken along the line 4—4 in Fig. 1.

Referring to the drawings, a metal, preferably non-corrosion steel such as steels containing weather-resisting properties such as chromium, copper or other metals, is used. The plane sheets of metal used must have sufficient thickness to give the desired strength when corrugated and formed into a proper wing contour. The plane sheets of metal are first united by double lock seams along their edges, as shown in Fig. 4, and the entire sheet which extends the length of the wing made up of a plurality of plane sheets united by the lock seams is then corrugated.

After corrugation the nose of the wing or leading edge of the wing is formed in the corrugated sheet by means of a bending brake having a plurality of rolls which coincide with the depressions of the corrugations and bend the corrugated sheet into the desired form. This bending which is at the present time being used in the sheet metal art for bending corrugated metal, maintains the cor-

rugations in the sheet or wing covering throughout the bending operation.

In the drawings, the plane sheets 1 are first united in double lock seams such as shown in Fig. 4, and the sheet then corrugated as shown in Figs. 1 and 3. The corrugated sheet is then formed into the desired wing contour and fastened by means of wood screws into the spar members 2 and 3. These spars as shown in Fig. 1, run longitudinally of the wing, furnishing a support throughout the length of the wing for the corrugated sheet. The corrugations in the wing covering extend in the line of flight and affect but little the wind or air forces acting upon the upper and lower surfaces of the wing. This corrugated sheet when doubled back over the spars is united along the trailing edge by means of rivets 4, spot welding, seam welding, crimping or otherwise.

It is understood that although a monoplane wing has been shown in the drawings, the construction is adapted to monoplanes, biplanes, triplanes or any other type of aeroplanes.

The corrugations in the sheets give the wing covering rigidity in the line of flight, and the spars furnish the required bracing and strength to withstand longitudinal stress. The construction provided is simple, is an efficient type of wing which can be manufactured quickly and easily, at less cost, and affords greater strength and less weight than the common type where fabric and wood are used with a plurality of ribs and braces or spars.

I claim as my invention:

1. An aeroplane wing comprising a plurality of pieces of metal united by double lock seams extending parallel to the line of flight to form a unitary sheet and unjointed transversely to the line of flight, said sheet corrugated in the direction of the line of flight and doubled back to form the wing contour with the free edges united along the trailing edge.

of the wing, the corrugations extending around the leading edge of the wing, said sheet mounted on horizontal spars extending transversely of the line of flight.

- 5 2. An aerofoil, comprising supporting spars extending longitudinally of the wing and a plurality of pieces of metal continuous as to length and united by double lock seams to form a unitary sheet the width of the air-
10 foil, said sheet corrugated in the direction of the line of flight and having joints in the sheets only parallel to the corrugations and doubled back to form the wing contour with the free edges united along the trailing edge
15 of the wing, the corrugations extending around the leading edge of the wing.

VICTOR C. NORQUIST.
